To all whom it may concern:

Be it known that I, JAMES MARSDEN, a subject of the Queen of Great Britain and Ireland, and a resident of Wigan, in the county of Lancaster, England, have invented and produced a new and original Design for a Pattern-Chart, of which the following is a specification, reference being had to the accompanying drawing, forming a part thereof.

The drawing is a plan view of a pattern-chart, showing my new design.

As shown in the drawing, the leading or material feature of my design consists in a pattern-chart having represented thereon the novel arrangements of patterns for a man's single-breasted morning coat and vest, as now described. At one side of the pattern-chart is shown the under side sleeve A, having inlay a and marks a' , the top sleeve B, the coat fore part C, having inlays c , coat-waist c' , and breast c'' , the neck-piece D, the fore part facing E, the skirt F, having inlay f , the pocket-welts G H I, the side body N, having inlays n , and the outside collar J. At the other side of the pattern-chart is shown 25 the inside collar K, the piece-up L for the fore part facing, the skirt-facing M, the back O, having inlays o' , the vest fore part P, having button-stand p , and pockets p' , the vest-facings Q and R, and vest-bottom facing S. 30
